(57) **CLAIM**

The ornamental design for a shock wave standoff assembly, as shown and described.

DESCRIPTION

FIG. 1 is a front perspective view of a shock wave standoff assembly showing our new design;

FIG. 2 is a rear perspective view of the shock wave standoff assembly of FIG. 1;

FIG. 3 is a top plan view of the shock wave standoff assembly of FIG. 1;

FIG. 4 is a bottom plan view of the shock wave standoff assembly of FIG. 1;

FIG. 5 is a left side elevational view of the shock wave standoff assembly of FIG. 1;

FIG. 6 is a right side elevational view of the shock wave standoff assembly of FIG. 1;

FIG. 7 is a front side elevational view of the shock wave standoff assembly of FIG. 1; and,

FIG. 8 is a rear side elevational view of the shock wave standoff assembly of FIG. 1.

The broken lines shown in the drawings illustrate portions of the shock wave standoff assembly that form no part of the claimed design. The dash-dot-dash lines represent boundaries of the claimed design and form no part of the claimed design.
